METHOD AND APPARATUS FOR SEALING
CONTAINERS

William D. Bell, Columbus, Ohio, assignor to Anchor Hocking Glass Corporation, Lancaster, Ohio, a corporation of Delaware

Application June 1, 1942, Serial No. 445,296

13 Claims. (Cl. 226—82)

My invention relates to method and apparatus for sealing containers. It has to do, more particularly, with a method of producing a partial vacuum within the sealed containers, and apparatus by means of which this can be readily accomplished.

This application is a continuation-in-part of my co-pending application Serial No. 325,393, filed March 22, 1940, which issued as Patent No. 2,284,631 on June 2, 1942, in which I disclose a method of producing the desired partial vacuum within the containers by first introducing into the space between a closure cap and the open mouth of the container to which it is to be applied a sufficient quantity of combustible gas to form a combustible mixture, igniting the combustible mixture, permitting the burning gases to expand, and then sealing the closure onto the container.

With a correctly proportioned mixture of combustible gas and air, combustion will spread quite rapidly through the mixture, with a rapid rise in temperature and a correspondingly rapid increase in volume and decrease in density of the burning gases.

By sealing the closure on to the container as nearly as possible coincidental with the greatest volume of the expanded burning gases, the head space of the sealed container will contain only the gaseous products of combustion of low density which, upon cooling to normal temperature, will result in a considerable reduction in pressure or partial vacuum.

This method of packaging not only results in the production of a partial vacuum in the head space of the containers but leaves within the head space an atmosphere of inert gases from which uncombined oxygen has been eliminated by the combustion. The flash temperature of the burning gases is quite high, resulting in effective sterilization of the entire head space of the containers, but it is of such short duration that it has no injurious effect upon either the cap, the container, or the material being packaged. For this reason this process results in better preservation of the contents of the container than it is possible to obtain by comparable prior art processes.

In my co-pending application Serial No. 325,393, I disclose apparatus for performing this basic process disclosed therein, in which a mechanically reciprocated sealing head is used to close the gap between the closure cap and the container and to completely seat the closure onto the finish of the container.

In the operation of this machine I found that the seating of the closure upon the mouth of the container brings about a very sudden drop in pressure within the container. This is due to the lack of oxygen to sustain combustion and to the very rapid absorption of heat from the burning gases by all of the interior surfaces of the head space. This extremely rapid drop in pressure is in all effects equivalent to the quick application of an external force tending to seat the closure upon the container, and is just as effective for that purpose as pressure applied by mechanical means.

When properly utilized, this significant fact makes possible a much simpler and more useful machine for sealing containers in which the operations can be performed at a high speed and while the containers are in uninterrupted motion. In addition the sealing operation may, when the type of closure requires, be performed in two or more steps, the vacuum being produced as the closure is applied to the container, to be followed later by a further mechanical operation to force the closure into frictionally sealed position on the container or otherwise anchor the closure to its container.

This method of initially sealing the cap on the container by use of a combustible mixture will result in the creation of a partial vacuum within the container which will be sufficient to hold the closure upon the container and prevent the access of air to the head space of the container. This method may be employed with various types of caps. With the side seal cap, which is now commonly in use especially on glass containers, the closure will be initially lightly seated upon the container but in sealing contact therewith. It may be desirable, subsequently, to subject the side seal cap to mechanical pressure to force it into its final frictional sealing position with relationship to the container. However, a substantial period of time may elapse between the initial application of the closure and its final sealing upon the container by mechanical means. Similarly, with this method, a cap may be employed which will be initially seated on the upper end of the container by atmospheric pressure and, subsequently, the skirt thereof may be contracted by mechanical means into association with a bead on the container which will serve to anchor the cap in position. Thus, an initial air-tight seal will first be made according to my invention and subsequently, even after the lapse of a substantial period of time, a permanent seal may be effected by means of mechanical pressure.

In the case of a top seal cap now commonly in use especially on glass containers, which may be used with my method, atmospheric pressure will seat the cap on the container in sealing contact therewith and the vacuum created within the container will be sufficient to hold the cap firmly, with an air-tight seal, upon the container. With this type of cap, no mechanical pressure sealing apparatus is required, if the container is sealed according to my method.

One of the objects of my invention is to provide a method and apparatus for applying caps to containers and to create a partial vacuum in the upper end of the containers wherein the cap is initially sealed on the container by atmospheric pressure.

Another object of my invention is to provide a method and apparatus of the type indicated for bringing about an extremely rapid drop in pressure in the head space of a container beneath a cap guided into position relative thereto which will cause sealing of the cap in sealing contact with the upper end of the container.

Another object of my invention is to provide a continuous method and apparatus for sealing caps on containers in the manner indicated in the preceding paragraphs.

Another object of my invention is to provide a continuous straight-line machine wherein the containers and caps may be continuously and progressively fed into association with each other, a combustible mixture is introduced into the head space of each container and ignited and the cap is drawn down into sealing contact with the container, the sealed container then being moved to a suitable position.

Another object of my invention is to provide a continuous machine of the type indicated in the preceding paragraph which is of simple and inexpensive construction but which will have a very high sealing capacity, will seal the containers effectively and will seal the containers economically.

Another object of my invention is to provide a machine of the type indicated having novel means associated therewith for guiding the caps into proper position to be applied to the containers and for preventing them from being applied in tilted position.

Another object of my invention is to provide a machine of the type indicated having novel means for guiding the containers into sealing position and for supporting them during the sealing operation.

Another object of my invention is to provide a method and apparatus of the type indicated for sealing containers, wherein a combustible mixture is employed to seal the cap on the container and to create an effective vacuum, which is of such a nature that the proper combustible mixture will be provided within and about the mouth of the container even though vapor or steam would ordinarily be present in the head space of the container at the beginning of the sealing operation.

In general, it is the usual practice to move the containers during the entire process of filling and sealing on constantly moving endless conveyors on which the containers may be placed more or less at random. It is the purpose of this invention to provide suitable apparatus for applying closures to the filled containers as they move along such a conveyor, the closure-applying or cap-feeding mechanism including in its construction means for producing a combustible mixture

of gas and air about the mouth of the containers as the closures are being applied, and for igniting the combustible mixture and seating the closures onto the containers to produce the desired partial vacuum. The invention also includes novel means for supporting the containers during their progress through the cap-feeding mechanism, and means for insuring the presence of a combustible mixture about the mouth of each container.

More specifically, I preferably employ a straight-line machine. This machine preferably embodies a straight-line continuously moving conveyer upon which the filled containers may be placed at random. Disposed above the conveyer in spaced relationship is a cap-feeding and guiding means which is adapted to guide caps into association with the upper ends of the containers as they move past the sealing station. At the sealing station, one of the caps is supported in such a position that it will be withdrawn from its support by a container moving into sealing position. Before each successive container reaches the sealing station, it is engaged by novel gripping and guiding means. This means serves to guide the container into proper position at the sealing station and to prevent tilting of the container during the sealing operation. At the sealing station, I provide means for guiding the caps into proper position to be applied to the containers and means for preventing them from being applied in tilted position to the containers.

I also provide at the sealing position, means for charging the proper combustible fluid within and about the open mouth of the container to form a combustible mixture and means for igniting said mixture at the proper instant. This means functions as each container moves into sealing position and engages the cap which is supported in downwardly inclined position by the cap-feeding and guiding means so that the upper end of the container will engage the skirt of the cap. A charge of combustible gas is supplied automatically when the cap is withdrawn from the supporting means by the container and this charge will be supplied into the head space of the container beneath the cap. Withdrawal of the cap from its support also automatically actuates igniting means which functions to ignite the charge of gas supplied to the head space of the container. The cap will be guided into position relative to the upper end of the container as the charge of combustible gas is ignited. Ignition of the combustible gas mixture causes a rapid expansion of the gaseous content of the head space of the container. As soon as combustion ceases, the products of combustion beneath the cap cool very rapidly with a consequent drop in pressure beneath the cap and within the head space of the container. The drop in pressure within the head space of the container is so rapid, as a result of the very rapid cooling of the products of combustion, that atmospheric pressure will snap the cap into sealing position and will be sufficient to initially seal the closure upon the container. This action is possible because the temperature of the gases entrapped below the cap is so high and the specific gravity so low that cooling, with a corresponding drop in pressure, is so rapid that the cap will be drawn down into firm sealing relationship with the upper end of the container.

After the cap is applied to the container and is initially sealed thereon in the manner indicated above, the containers may be moved to a station where mechanical means is used to effect

permanent sealing of the containers. Whether or not the mechanical means is used for effecting permanent sealing will depend upon the type of closure being used to seal the container. With some caps, mechanical pressure will be desirable to effect the final sealing but this mechanical sealing may occur a considerable period of time after the initial sealing has been effected. With some caps, such as a top seal cap, the final sealing with mechanical pressure will not be necessary.

In order to aid in understanding my method of applying the closures and of producing the partial vacuum, an embodiment of the invention is illustrated in the accompanying drawings. However, it is to be understood that there is no intention to limit the invention to this detailed embodiment.

In these drawings similar character of reference designate corresponding parts and :

10 Figure 22 is a perspective view of a portion of the mechanism shown in Figure 21.

Figure 23 is a top plan view, partly broken away, of the mechanism shown in Figure 21.

With reference to the drawings, and particularly to Figure 1, I have illustrated one form of my apparatus as comprising generally a supporting table and conveyer unit 1, a vacuumizing and sealing unit 2, a container gripping and guiding unit 3 and a mechanical pressure sealing unit 4.

The unit 1 will feed the containers continuously into association with the unit 2 where a cap will be guided into association with the upper end of the container, a combustible mixture will be charged beneath the cap and the mixture will be ignited, the rapid drop in pressure in the head space resulting from this serving to draw the cap down onto the container. While the container is associated with unit 2, it will be gripped by the unit 3. The unit 4 will serve to apply mechanical sealing pressure to the cap and may or may

25 not be used, depending upon the type of cap employed.

The unit 1 is in the form of a table having four legs 5 which support a top plate 6 and a base plate 7. As shown best in Figures 1, 3 and 4, intermediate the side edges of the top plate 6 a pair of longitudinally extending spaced strips 8 are secured thereto. These strips extend the full length of the table. Intermediate the strips 8 a third longitudinally extending strip 9 is provided which is secured to the top plate 6. These three strips serve to provide longitudinally extending channels 10 (Figure 3) on top of the plate 6 which receive a pair of chains 11. The chains 11 are of the sprocket type and extend longitudinally through the channels 10. The chains slide on the top surface of plate 6 and project slightly above the bars 8 and 9 so that they will support the bottom of a container, in the manner shown in Figure 3, out of contact with the bars.

40 The chains 11 are endless chains and pass around double sprocket units 12 and 13 disposed at opposite ends of the table. The sprocket units 12 and 13 are rotatably supported by brackets 14 disposed at opposite ends of the table and being bolted thereto, as shown in Figure 1. The bracket 14 which supports the sprocket 12 is provided with a vertical bearing 15 which receives a rotatable shaft 16. This shaft 16 has a bevel pinion 17 keyed on its upper end which meshes with a bevel gear 18 keyed on the outer end of the horizontal shaft 19 which supports the sprocket unit 12. The unit 12 is also keyed on the shaft 19. The lower end of shaft 16 has a pulley 20 keyed thereon. It will be apparent that rotation of this pulley 20 will drive the conveyer chains 11.

45 The pulley 20 is driven by means of an endless belt 21. This belt 21 is driven by a pulley 22 which is keyed on the vertical shaft 23 that is rotatably carried by bearing plates 6 and 7. The pulley 22 is disposed intermediate the height of the shaft 23. The lower end of the shaft 23 has another pulley 24 keyed thereon. This pulley 24 is driven by means of a belt 25 which is driven by 50 the lower pulley 26 of a multiple pulley unit 27.

55 The pulley 20 is driven by means of an endless belt 21. This belt 21 is driven by a pulley 22 which is keyed on the vertical shaft 23 that is rotatably carried by bearing plates 6 and 7. The pulley 22 is disposed intermediate the height of the shaft 23. The lower end of the shaft 23 has another pulley 24 keyed thereon. This pulley 24 is driven by means of a belt 25 which is driven by 60 the lower pulley 26 of a multiple pulley unit 27.

65 The pulley 20 is driven by means of an endless belt 21. This belt 21 is driven by a pulley 22 which is keyed on the vertical shaft 23 that is rotatably carried by bearing plates 6 and 7. The pulley 22 is disposed intermediate the height of the shaft 23. The lower end of the shaft 23 has another pulley 24 keyed thereon. This pulley 24 is driven by means of a belt 25 which is driven by 70 the lower pulley 26 of a multiple pulley unit 27.

keyed on a shaft 28. The shaft 28 is driven by a gear unit 29 which, in turn, is driven by an electric motor 30. The units 29 and 30 are supported by the base plate 7. Thus, whenever the motor 30 is energized, the chain conveyer will be driven continuously.

The unit 2 is disposed at a level spaced vertically above the chain conveyer depending upon the height of the container being sealed. The unit 2 is disposed in alignment with the conveyer substantially midway between the side edges of the table. Furthermore, it is disposed intermediate the length of the conveyer and table. Containers placed at random on the chain conveyer behind the unit 2 will be moved progressively, by the continuously moving conveyer, into association with the unit 2.

The unit 2 includes a downwardly and forwardly inclined cap chute 31. This chute 31 (Figure 1) comprises a pair of spaced guide rails 32 which are in the form of angle members. These rails 32 are properly positioned to support caps 33 which are disposed in edge-to-edge relationship. A bar 34 disposed intermediate guide rails 32 and above the rails serves to prevent the caps from riding up on each other as they slide down the chute. The upper end of the bar 34 is turned upwardly, as at 35, to facilitate insertion of the caps. The lower end of the bar 34 is supported by an inverted U-shaped bracket 36 which is secured to the rails 32. The lower end of the bar 34 is turned downwardly, as at 34a (Figure 2).

The lower ends of the guide members 32 are rigidly secured to the forward ends of a pair of forwardly projecting portions 37 (Figure 1) of a block 38 by means of screws 39a. This block is illustrated in detail in Figures 12 and 13. The block 38 is horizontally disposed and its rear end is rigidly secured by means of screws 39a (Figure 2) to a pair of upstanding supports 39 which have their lower ends rigidly secured to the plate 6 on opposite sides of the chain conveyer. The guide members 32 rest on inclined ledges 37b formed on the inner surfaces of portions 37 as shown in Figure 12. These portions 37b determine the inclination of the members 32. A second block 40, somewhat similar to block 38, is secured to the upper surface of block 38 by means of screws 41. This block 40 is provided with forwardly projecting portions 42, adapted to be disposed in alignment with the portions 37 of block 38. It is also provided with a forwardly and downwardly inclined front edge 43, between portions 42, which form continuations of the surfaces 37b. The members 32 will also rest on this surface 43 and may be secured thereto by means of screws passing into threaded openings 44 formed therein.

As shown best in Figures 1 and 2, the bracket 36 carries a downwardly and forwardly extending rigid arm 45 which is supported midway between and above members 32. This arm 45 extends a substantial distance beyond the lower ends 46 of members 32 and is provided with an upturned lower end 47. It will be noted from Figure 2 that the member 34 terminates at a point above the lower ends 46 of the members 32. Supported above the arm 45 in alignment therewith is a flat spring 48. This spring 48 is attached at its upper end to a block 49 secured to bracket 36 and serving to space the upper end of member 48 from the upper end of member 45. The lower end of the member 48 will normally rest on the upturned end 47 of member 45. The extreme lower end of

member 48 has a bearing portion 50 formed thereon which is provided with a transverse bearing sleeve in which a shaft 51 is mounted for rotatable and slide movement. A pair of rollers 52 are keyed to the outer ends of this shaft 51. Spacer sleeves 53 are provided on shaft 51 between rollers 52 and member 50 to limit longitudinal movement of the shaft. The sleeves 53 are of a proper length to permit limited axial movement of the shaft 51 in bearing 50. Each of the rollers 52 is provided with a circumferential flange 54 at its outer side. The flanges 54 are spaced apart a distance corresponding to the diameter of the cap 33. Thus, flanges 54 of the rollers will engage the side edges of the cap while the circumferences 55 of the main part of the rollers will engage the top surfaces of the caps adjacent their edges. It will be apparent that the rollers 52 are free to rotate and are also free to move laterally to a limited extent. Normally the lower end of flat spring 48, which carries the rollers, will contact the upturned portion 47 of member 45 and the rollers will be supported in the full line position indicated in Figure 2. However, the rollers can be moved vertically against the action of spring 48, as shown by dotted lines in Figure 2.

Associated with the lower end of the cap chute is a lever 56. This lever is illustrated best in Figures 2 and 4. It is disposed between the guide rails 32 adjacent the lower ends thereof. It is disposed in alignment with the lower end of member 34 and its lower end terminates substantially at the lower end of member 34. This lever 56 has its rear end pivotally mounted, as at 57, to a supporting yoke 58. The yoke 58 is carried by a housing 59 which is supported on the upper surface of the block 38 adjacent its rear edge. The housing 59 includes a bracket 60 to which the member 58 is directly connected. This bracket 60 has a depending portion 61 which has an opening that receives a grommet for a cable 63 that connects to the switch disposed in housing 59. The rear end of lever 56 is formed integral with a sleeve 64, rotatably carried by yoke 58. One end of sleeve 64 carries an integral depending trigger 65. The lower end of this trigger is adapted to engage a push button 66 of the switch 59 when the lever 56 is moved to a certain position. The lever 56 has a lower inclined portion 67. The extreme lower end 68 of the portion 67 normally projects above the horizontal surfaces of guide members 32 of the cap feed, as shown by the full lines in Figure 2. However, as a cap passes between the downturned portion 34a of member 34 and the end 68 of lever 56, the lower end of the lever is forced downwardly and rearwardly into the dotted line position indicated in Figure 2. The block 40 is provided with a notch 69 (Figure 12) and the upper corner of the vertical forward surface 70 of block 38 is provided with a notch 71. These notches 69 and 71 are disposed in alignment and serve to receive the forward portion 67 of lever 56. The lever 56 is normally held in the raised full line position of Figure 2 by means of a plunger 72 which engages the lower edge thereof at a point adjacent the rear end thereof. This plunger 72 is associated with a gas supply control valve 73 which is carried by the block 40. The plunger 72 is normally held in raised position by means of a spring 74 associated with the valve 73. When in raised position, the trigger 65, as shown by full lines in Figure 2, will not engage the push button 66 of switch 59.

The caps which I use for sealing the containers

may be of various types. In Figures 1 to 17, inclusive, I have illustrated side seal caps being used. These side seal caps are commonly used for sealing glass jars of the type shown in the drawings and indicated by the numeral 75. This glass jar is provided with a reduced mouth having a vertical sealing surface 76 and a tapered finish 77. The cap 33 is shown as comprising a disk-like body portion 78 having a depending peripheral skirt 79. This skirt carries on its interior a compressible gasket 80. When the cap 33 is forced down into telescoping relationship with the upper end of the container 75, the gasket 80 will contact with the vertical surface 76 forming a tight frictional seal. However, it is to be understood that my invention is not limited to the particular type of container or cap shown in the drawings.

The caps fed into the chute 31 will be in edge-to-edge relationship, as previously stated. The lowermost cap will slide down to the full line position shown in Figure 2 until it engages the rollers 52. The weight of the caps in the chute will be sufficient to force the lowermost cap downwardly past the cooperating portion 34a of member 34 and the portion 67 of lever 56. The lowermost cap will move downwardly until its lower edge moves between the flanges 54 of the rollers 52 and the surfaces 55 of the rollers engage the top surface of the cap. Then downward movement of the lowermost cap will be stopped. At this time, the lower end of member 48 will be contacting the upturned portion 47 of member 45. The lowermost cap is held in the chute by the rollers and is prevented from tilting by portion 34a. Consequently, the lowermost cap will be held in the full line position shown in Figure 2, depending from the cap chute and being in such an inclined position that the forward portion of the flange 79 will be engaged by the upper end of the container 75 being moved into sealing position by the chain conveyor.

As the continuously moving chain conveyor moves the container 75 beneath unit 2, the upper end of the container engages the skirt of the cap and withdraws it from the chute. As the cap is withdrawn from the chute, the cap pivots about the rear edges of the rollers depressing the lower end 67 of lever 56. The rollers 52 will be raised during this action, as shown by dotted lines in Figure 2. The rollers 52 will also move laterally, if necessary, to permit lateral alignment of the cap and container. As the container continues to move, the cap will be guided into cooperative position with the upper end thereof and will be positioned thereon. The successive steps of this operation are illustrated best in Figures 9, 10 and 11.

In order to insure the proper seating of the cap upon the finish of the container, I provide a pair of guide rails 81. These rails are so positioned that they provide a fulcrum about which the cap rotates to an approximately level position as it is seated upon the container. These guide rails extend longitudinally in spaced relationship and have their rear ends rigidly connected, as at 82, to a yoke 83. This yoke 83 is supported on the rear portion of block 38 by means of a screw 84 passing through an opening formed in yoke 83 midway between its ends. As shown in Figures 9 and 10, the head of the screw 84 fits into the opening in such a manner that limited universal movement of the yoke relative to the block 38 will be permitted. The guide rails 81 are spaced apart laterally a dis-

tance slightly greater than the diameter of the reduced upper portion of the containers. Thus, the upper ends of the containers may move freely therebetween and they will align with the containers. However, the spacing between rails 81 is such that the skirt of the cap will be engaged, at diametrically opposed points, when the cap moves downwardly to a predetermined position, as shown by the full lines in Figure 10. As the cap is removed from the chute, its rear edge moves off the block 40 and the guide rails 81 exert a leveling action on the cap, as shown by the dotted lines in Figure 10, and will prevent the cap from being applied in tilted position on the container. The guide rails 81 are at such a level, as shown in Figure 11, that when the gasket 80 of the cap is in contact with the vertical surface 76 of the container, the skirt of the cap will not be in contact with the rails 81. Thus, the rails will cooperate with the rollers 52 to level the cap relative to the upper end of the container as it is withdrawn from the chute. However, the rails 81 will not interfere with the cap being drawn down into sealing contact with the upper end of the container. The rails 81 may swing laterally or move vertically to a limited extent. Thus, they will cooperate with the rollers 52 in positioning the cap laterally relative to the container. Thus, as the successive containers continuously move beneath the lower end of the cap chute, each container will withdraw a cap which will be guided into position and leveled into horizontal position relative to the upper end of the container.

As each cap is engaged by a container it tilts so that its rear edge depresses the lever 56. It continues to ride on the block 40, holding the lever 56 depressed and the valve 73 open, as indicated by the dotted lines in Figure 9. As the cap is further withdrawn, the rear edge thereof is no longer supported by block 40 but only by the lower end of lever 56, as shown in Figure 10. This will depress lever 56 further and it will be depressed sufficiently to move trigger 65 into a position to actuate the movable control member 66 of the switch on housing 59. The mechanism which is controlled by the switch in housing 59 and by the valve 73 will be described hereinafter.

In order to supply the proper combustible mixture beneath the cap, as it is being withdrawn from the chute, I provide the arrangement now to be described. As shown best in Figures 2, 5, 9, 10, 12 and 13, the forward vertical surface 70 of the block 38 has small ignition chambers 85 formed therein which are open at their forward ends. These chambers 85 communicate at their rear ends with gas and air passageways 86 extending longitudinally of block 38. One chamber 85 is provided adjacent each side of the block. Intermediate the passages 86 a longitudinally extending air and gas passageway 87 is formed which has its forward end open at the surface 70. All of the passages 86 and 87 are connected at their rear ends, as shown best in Figures 7 and 8, to a transversely extending air chamber 88 formed in the block 38. Intermediate their ends, all of these passageways are provided with branch passages 89 formed in member 38 and directed rearwardly and upwardly. These passages 89 communicate at their upper ends with a transversely extending gas chamber 90 formed in the upper surface of block 38. A gasket 91 is provided between the blocks 38 and

40 to provide a fluid-tight joint between these members. The gasket 81 is provided with an opening 82 which permits communication between the gas chamber 90 and a chamber 93 in which the gas-control valve 73 is located, by means of an upwardly and rearwardly directed passage 94 formed in block 40.

As shown in Figure 5, an inlet passageway 95 is formed in the block 40 for supplying a suitable combustible gas to the chamber 93 in which the valve 73 is disposed. The passageway 95 is connected by a conduit 95a to a suitable source of combustible gas. The chamber 93 has a large cylindrical lower portion 96 and an upper smaller cylindrical portion 97. The valve is in the form of a hollow vertically movable member 98 of similar shape. The spring 74 normally forces this member 98 upwardly. The enlarged lower portion of member 98 has an upstanding knife-edge annular rib 99, formed thereon, which contacts with a sealing ring 100 carried by the top wall of the lower enlarged portion 96 of chamber 93. When the valve is seated in this manner, gas cannot flow from the lower portion 96 of member 98 into the upper portion 97 thereof. Consequently, gas cannot reach the passage 94 which leads into the chamber 90. However, when plunger 72 is forced downwardly and moves member 98 downwardly, the rib 99 is unseated from gasket 100. Then gas will flow from the portion 96 of chamber 93 into the portion 97 thereof, through passage 94 into the chamber 90. From the chamber it will flow down through passageways 89, into passageways 86 and 87. A needle valve 101 is provided in the passage 94 for regulating the amount of gas which will flow through this passage. This needle valve has a threaded outer portion 102 threaded into block 40. A spring 103 of the compression type is provided on the outer portion of the needle valve between the knurled knob 102a formed thereon and the outer surface of the block 40. The spring will hold the needle valve in adjusted position.

The air chamber 88 formed in block 38 has one end closed and its opposite end communicates with an air passage 104 formed in a block 105 secured to the side edge of block 38 as shown in Figures 4 and 12. The block 105 has a rearwardly extending passageway 106 formed therein at right angles to the passage 94. A valve 107 is threaded into block 105 and into the end of passageway 104. By means of this valve 107, the amount of air flowing into the chamber 88 may be controlled. The rear end of passage 106 is in communication with an air conduit 108. This conduit 108 leads to a fan or air pump 109 supported on the base plate 1.

The fan 109 is illustrated best in Figures 15 and 16. It comprises a cylindrical housing 110 having an impeller 111 rotatably mounted therein. An outlet 112 communicates with the conduit 108. The impeller 111 is provided with an upwardly extending shaft portion 113 which extends through a hub portion 114 projecting upwardly from the housing. This hub portion is provided with a series of air inlet openings 115. When the impeller 111 is rotated, air is drawn through openings 115 by the impeller and is forced out through the outlet 112. The shaft portion 113 carries a driving pulley 116 which is keyed thereon. This pulley 116 is driven by means of a belt 117 which is driven by the pulley section 118 of the multiple pulley unit 27.

The fan unit 109 will serve to force air continuously through the line 108 and into the chamber

88 and through the passages 86 and 87, beneath the depending cap. The air impinging against the cap, as shown best in Figure 7, will be deflected into the head space at the upper end of the filled container and will serve to displace any vapor or steam from the upper end of the container. This will insure proper supply of air for combustion, particularly if the contents of the container have been processed with steam or are hot and are emitting vapor. As the container moves along and withdraws a cap, the valve 73 is unseated and this allows gas to reach the passages 86 and 87, as previously indicated. The air and gas mixture will then be forced out of the forward end of passage 87 beneath the cap and into the upper end of the container as shown in Figure 8. The air and gas mixture from passages 86 will first enter chambers 85 and will then pass out into the space beneath the cap.

When the space beneath the cap and the head space of the container has been supplied with a proper charge of combustible mixture, this mixture will be ignited. This is accomplished by providing spark-producing means in association with the ignition chambers 85. The spark-producing means, as shown in Figure 6, comprises spark plug units 119 which may be of any suitable type. The points 120 of these spark plugs are within the chambers 85. These spark plugs 119 are connected to cables 121. The switch in housing 59 is adapted to control the operation of the spark plug units 119. The units 119 are carried by and are insulated from the blocks 38. They may be removably held in position by means of setscrews 122. When the push button 66 of switch 59 is pushed inwardly, this will energize the spark plugs and ignite the gas and air mixture flowing out of the chambers 85. This will ignite the combustible mixture, previously charged beneath the cap and into the head space, throughout. The spreading of the ignition throughout the mixture is facilitated by the turbulence created by the flow of air from the chamber 88, through the passages 86 and 87 and out into the space beneath the cap. As previously indicated, the switch 59 will be actuated shortly after the valve 73 has been actuated to supply the combustible gas to the passageways 86 and 87.

Thus, a charge of a combustible mixture is supplied within and about the open mouth of the container and this charge is then ignited. The ignition will occur as the cap is being withdrawn from the lower end of the cap chute, as indicated in Figure 8. The cap will be guided into position relative to the upper end of the container. The ignition of the combustible gas mixture causes a rapid expansion of the gaseous content of the head space of the container. As the combustion subsides, the products of combustion beneath the cap cool very rapidly with a consequent drop in pressure beneath the cap and within the head space of the container. As the combustion ceases, the cap has been leveled into horizontal position relative to the upper end of the container. The drop in pressure within the head space of the container is so rapid, as a result of the very rapid cooling of the products of combustion, that atmospheric pressure will press the cap into sealing position as shown in Figures 8 and 11 and will be sufficient to hold the cap down on the container with the gasket 76 in sealing contact with the container. The drop in pressure will serve to draw the cap down into sealing contact with the upper end of the

container and may draw the skirt downwardly so that the gasket will be in partly telescoping relationship to the surface 76, as shown in Figures 8 and 11. However, the gasket will always be drawn into firm sealing contact with the upper end of the container by the reduction in pressure in the head space of the container beneath the cap. Thus, the cap is initially sealed on the upper end of the container by the ignition of the explosive mixture charged beneath the cap.

In order to guide the containers laterally of the chain conveyer into proper association with the unit 2, I provide diverging guide members 39b which are shown best in Figure 4. These guide members 39b are carried by the vertical supports 39 intermediate the height thereof, as shown in Figure 2, and extend rearwardly therefrom. As each container is moved into association with the unit 2, the members 39b will engage it and position it in alignment with the unit 2.

In order to grip the containers and prevent rearward slipping thereof as each container withdraws a cap from the cap feed, I provide novel container gripping means which functions as the container engages the cap and withdraws it from the chute. It is particularly important to provide this means when small diameter containers are being fed inasmuch as they have a tendency to upset rearwardly when the upper end of the moving container engages the stationarily supported dependent cap. This gripping means is shown best in Figures 1 to 4, inclusive, and 17.

This gripping means comprises a pair of gripping rollers 123. These rollers are disposed at opposite sides of the chain conveyer and adjacent the unit 2. They are disposed horizontally at such a level spaced above the plate 6 that the containers supported by the conveyer and moved successively therebetween will be properly supported by the rollers. Each of the rollers 123 comprises a wheel 124 (Figure 1) upon which a pneumatic tire 125 is mounted. This tire may be inflated by means of a valve 126. The wheel 124 is provided with a hub 127 which is keyed to the upper end of a shaft 128. The shaft passes down through the plate 6 and is rotatably mounted in a bearing 129 thereon. The center portion of the wheel is normally covered by a removable plate 130. Each of the shafts 128 has a sprocket 131 keyed on its lower end below the plate 6. An endless chain 132 passes around one of these sprockets and around a smaller sprocket 133 keyed on the upper end of shaft 23. This chain 132 also engages the other sprocket 131. Thus, the shaft 23 will serve to drive the rollers 123 in opposite directions. These rollers will be driven in such a manner that the peripheral portions thereof will travel in the same direction and at the same linear speed as the conveyer chain.

As indicated in Figure 17, as the container 75 is brought between the converging surfaces of the rollers 123, by the continuously moving conveyer, the container is driven firmly but resiliently between the rollers. It will be noted from Figures 2 and 4 that the axes of rollers 123 are substantially in alignment with the lower end of the cap feed. Consequently, the rollers will exert their greatest gripping force on the container as the container is withdrawing the cap from the lower end of the cap feed. This is where the gripping action is needed most. Thus,

with this structure, there will be no danger of the container being upset as it withdraws the cap from the cap feed. The amount of the gripping action, that is, the resilient force exerted by the rollers on the container, may be varied by variations in pressure of the air within the pneumatic tires 125. As the container moves along, it will pass a line extending through the axes of these rollers and will therefore reach 10 the diverging portions of the roller and will be released.

After the caps have been applied to the containers in the manner indicated, the containers may be subjected to the mechanical pressure 15 sealing unit 4 or its equivalent. Whether or not they are subjected to this unit 4 will depend upon the type of cap being used to seal the containers. If it is a side seal cap of the type previously described, it will be desirable to use such a mechanical sealing unit as the unit 4. However, the unit 4 need not necessarily be mounted directly adjacent the unit 2, although it is preferred to have it so mounted. The mechanical pressure sealing may occur after a considerable 20 period of time has elapsed subsequent to the initial sealing by the combustible mixture.

The unit 4 is illustrated best in Figures 1, 2, 4 and 14. It comprises a vertically disposed wheel 134 mounted in substantially the same 30 plane as the chain conveyer. This wheel is disposed at a proper level to force the cap down into the final sealing position on the containers with the gasket 80 in frictional contact with the vertical surface 76 of the container.

35 The wheel 134 is provided with a band 135 of compressible material. Thus, hub 136 of the wheel is keyed on a horizontal shaft 137. This shaft is rotatably mounted in a bearing 138 provided on the upper end of a vertical support 139. The support 139 comprises an upper portion 140 which carries the bearing 138. This upper portion 140 has a socket in its lower end which receives the upper end of a rod 141 and is held in position in the socket by a setscrew 142. The lower end of member 140 rests on a sleeve 143 which is threaded in the upper end of a sleeve 144. The sleeve 144 is clamped to the plate 6 by means of clamping means 145. The rod 141 is free to slide vertically in members 143 and 50 144. A compression spring 146 surrounds the lower end of rod 141 and its lower end bears against a nut 147 threaded on the rod. The upper end of the spring bears against the lower end of member 144. Thus, the wheel 134 is resiliently mounted so that it can move upwardly against the force of spring 146 as a container moves beneath the wheel. The vertical position of the wheel may be varied by threading the sleeve 143 up or down on the member 144.

55 The shaft 137 has its outer end disposed in a bearing 148 which loosely engages the shaft in order to permit the necessary vertical movement of the inner end of the shaft. This end of the shaft 137 carries a worm gear 149 which engages with a worm 150 formed on the upper end of the vertical shaft 151. The lower end of this shaft is carried by a bearing (not shown) secured to the vertical wall of the table. The lower end of this shaft 151 has a pulley 152 keyed thereon. This 60 pulley 152 is driven by a belt 153. The belt 153 is driven by the pulley 154 of the multiple pulley unit 27. The wheel 134 will be driven so that its lower periphery will travel in the same direction and at the same speed as the chain conveyer. 70 Consequently, as the containers are moved be-

neath the wheel, the cap will be engaged by the wheel and forced into the final sealing position.

In the operation of my machine, the filled containers are positioned on the chain conveyer, regardless of spacing, and the conveyer will first carry the containers to the unit 2. As they move into association with this unit, they will be gripped by the unit 3. At the unit 2, one of the caps will be engaged by the container and will be withdrawn from the cap chute. A charge of combustible fluid will be supplied within and about the open mouth of the container to form a combustible mixture. However, before the combustible gas is supplied beneath the cap, the air current supplied by the fan will have removed any steam or moisture therefrom and a better combustible mixture will thus be obtained. The combustible mixture will be ignited as the cap is being withdrawn and guided into horizontal position. Ignition of the combustible gas mixture causes a rapid expansion of the gaseous content of the head space of the container. As soon as combustion ceases, the products of combustion beneath the cap cool very rapidly with a consequent drop in pressure beneath the cap and within the head space of the container. The drop in pressure within the head space of the container is so rapid, as a result of the very rapid cooling of the products of combustion, that atmospheric pressure will press the cap into sealing position and will be sufficient to initially seal the closure upon the container. After this initial sealing action, the container moves into association with the unit 4 which will apply mechanical pressure to effect the final sealing operation. The vacuumizing and sealing operation is performed during the continuous movement of the container through the machine.

In Figure 18, I have illustrated my method and apparatus being used in connection with a different type of cap and container. The cap is provided with a skirt 79a adapted to be deformed around a bead 76a on the container to mechanically anchor the cap in position. The cap is provided with a side seal gasket 79a and with a top seal gasket 79b. The cap is applied to the container by the unit 2 in exactly the same manner as before. The initial seal will be effected by drawing down the cap with the gasket 79b in contact with the upper end of the container. The vacuum created within the container will be sufficient to hold the cap in position. Then, the container with the cap thereon is moved to another sealing unit 4a which consists of a chuck 4b that is adapted to surround the skirt of the cap and to subject the skirt to a bending action, indicated in Figure 19, to cause the gasket 79a to engage the bead 76a and anchor the cap in position. Thus, the seal is initially effected by the unit 2 and the mechanical seal is later effected by the unit 4a. A long period may elapse between these two sealing operations.

In Figure 20 I illustrate my method and apparatus being employed with a cap of the top seal type. This cap is provided with a top seal gasket 79c adapted to seat upon the top edge of the container. The cap is applied by the unit 2 exactly as before. However, with this type of cap, it will not be necessary to use any mechanical sealing unit. The vacuum created within the container by the unit 2 will serve to retain the cap in position.

In Figures 21, 22 and 23, I have illustrated a modification of my machine. The chain conveyer

unit is the same as in the other machine. The unit 3a for gripping and supporting the containers as they withdraw the caps from the cap chute, in this instance, embodies a pair of endless belts 123a disposed at opposite sides of the conveyer. Each of the belts is carried by a forward idler pulley 155 and a rear driving pulley 156. The pulley 156 is keyed on a driving shaft 157 which is vertically supported for rotation in a bearing 158. The pulley 155 is carried by a pin mounted on the forward end of a horizontal arm 159 which has its rear end mounted for rotation about the shaft 157. A leaf spring 160 is carried by the bearing 158 and engages the outer edge of bar 159 adjacent its rear end. Thus, the spring 160 serves to swing the forward end of the bar 159 inwardly. The shaft 157 is driven in such a manner as to drive the belts 123a in the same direction and at the same linear speed as the chain conveyer. It will be apparent from Figure 23 that the forward end of the belt units will converge towards each other. The normal distance between the forward ends of these belt units will be slightly less than the diameter of the container being sealed. Consequently, as the container moves between these belt units, it will be gradually gripped. Stops 161 are carried by the bearings 158 for engaging the inner edge of bars 159 and for limiting their inward swinging movement. As shown in Figure 23, the rollers 155 are disposed adjacent the lower end of the cap chute 31a. Thus, the containers will be firmly gripped adjacent the lower end of the cap chute where the containers will engage the caps. Thus, tilting of the containers rearwardly will be prevented.

The cap chute 31a in this instance is practically the same as before. In this machine, the fan for supplying the air current beneath the cap at all times is not employed. In sealing some products, this will not be necessary. In this machine, instead of employing a spark-producing means for igniting the gas mixture, I provide a constantly burning pilot flame.

It will be noted that the lower end of the cap chute has a block member 38a associated therewith. This block member has two forwardly directed orifices 86a at the forward edge thereof. The rearwardly extending gas passage 87a, formed in this block, connects these orifices to a flow control valve 73a. The valve 73a is normally seated, as shown in Figure 21. It is adapted to be unseated by moving the plunger 72a downwardly. When unseated, the passage 87a is connected to a gas supply passage or chamber 88a. A suitable gas supply conduit 88c is connected to this chamber 88a. A small outlet passage 88b leads from the chamber 88a and is connected to a gas line 63a. This gas line 63a connects to a pilot valve 120a which is cooled by fins 120b. The forward end of this pilot valve is provided with an orifice 120c which is upwardly directed and extends through the bottom 120d of a tubular member 120e. This member is located at one side of the lower end of the cap chute. Openings 120f are provided in the wall of the member 120e. This member receives an open top flue member 120g which telescopes therewith. An opening 120h leads from the member 120e to a point which will be beneath the lowermost cap in the chute. The pilot burner orifice 120c will always provide a constantly burning flame because the line 63a is connected to a constant supply of gas. An igniting nozzle member 120i extends through the wall of the chamber 120e towards the opening

120h. The member 120i is connected by a passage 87b to the passage 87a which is connected to the valve 72a.

As soon as the control valve 73a is actuated, a charge of gas will be forced outwardly from the orifices 86a and will mingle with the air beneath and about the cap to form a combustible mixture. At the same time, flow of gas will occur through the igniting nozzle 120i, which is adjacent the pilot burner orifice 120c. The gas issuing from member 120i will be ignited as it passes the pilot flame and will, in turn, ignite the combustible mixture beneath the cap into which it is projected through opening 120h. There naturally occurs a slight interval of time between the issuance of gas from the orifices 86a and the ignition of the mixture beneath the cap by the flaming gas issuing from member 120i through opening 120h because of the longer path traversed by the gas issuing from member 120i. This delay is sufficient to permit the intermingling of the gas issuing through orifices 86a with the air in the extended head space beneath the cap.

The plunger 72a is adapted to be moved downwardly by means of a lever 56a. This lever normally projects up into the cap chute substantially the same as lever 56. The lever 56a will be moved downwardly when a cap is withdrawn from the chute and will force the plunger 72a downwardly and unseat valve 73a, allowing a charge of gas to flow through the nozzles 86a. As soon as the cap is withdrawn, the valve will be automatically closed. Thus, the sealing operation with this form of apparatus will be practically the same as before.

It will be apparent from the above description that I have provided a sealing machine and method for applying caps to containers and for creating a partial vacuum in the upper end of the containers wherein the cap is applied to the container in sealing contact therewith by atmospheric pressure. My apparatus and method will continuously apply the caps and seal the containers during their progressive movement.

During sealing of the containers, a combustible charge will be supplied beneath the caps and will be ignited at the proper instant to draw the caps down into sealing position. The drop in pressure beneath the cap within the head space of the container is so rapid, as a result of the very rapid cooling of the products of combustion, that atmospheric pressure alone is sufficient to seal the cap upon the container when it is supported in proper relationship to the upper end of the container. The combustion of the charge not only expands and displaces the air in the head space of the container, but also consumes the oxygen therein. Thus, the rarefied gases which remain in the head space of the container after sealing are inert products of combustion. The desired vacuum is produced without the introduction of moisture and, consequently, the method is particularly useful for sealing dry products.

Various other advantages will be apparent from the preceding description, the drawings and the following claims.

Having thus described my invention, what I claim is:

1. The method of sealing a cap on a container which comprises guiding a cap into position over the container and while guiding the cap into such position first passing a current of air beneath the cap and into the head space of the container to

remove vapor therefrom and then charging a combustible fluid beneath the cap and into the head space of the container to form a combustible mixture, and igniting said combustible mixture to cause the gases beneath the cap and in the head space of the container to expand and to subsequently contract and seating the cap on the container as combustion subsides in sealing position relative thereto.

10 2. The method of sealing a cap on a container which comprises positioning the cap over the container and while maintaining the cap in such position sweeping the space beneath the cap and about the mouth of the container with air to remove vapor therefrom, then charging such space with a combustible fluid to form a combustible mixture, and igniting said combustible mixture to cause the burning gases to first expand and then contract and means for seating the cap on the container while the burning gases are expanded.

15 3. A method of sealing and preserving packaged material which comprises sweeping the space within and about the open mouth of a container with air to remove vapor therefrom, then charging such space with a combustible fluid to form a combustible mixture, and igniting said combustible mixture to cause the burning gases to first expand and then contract and sealing the container as the gases contract.

20 4. A method of closing and sealing a container which comprises supplying a charge of air into the container to remove vapor therefrom, supplying a charge of combustible fluid into the container so that it will mix with the air, igniting the combustible mixture so produced, and then sealing the container.

25 5. The method of continuously sealing caps on containers which comprises moving the containers continuously, guiding a cap into position over each successive container during its continuous movement, and while guiding the cap into such position charging a combustible fluid beneath the cap and into the head space of the container to form a combustible mixture, and igniting said combustible mixture to cause the gases beneath the cap and in the head space of the container to expand and to subsequently contract, and means for seating the caps on the containers while the burning gases are expanded during continuous movement of the container.

30 6. A method according to claim 5 wherein a charge of air is first supplied beneath the cap before the combustible fluid is supplied to remove vapor therefrom.

35 7. The method of continuously sealing caps on containers which comprises continuously moving the containers, supporting caps in position to be engaged by successive containers to apply a cap to each container, and while the cap is being applied to the container charging a combustible fluid beneath the cap and into the head space of the container to form a combustible mixture, and igniting said combustible mixture to cause the gases beneath the cap and in the head space of the container to expand and to subsequently contract and means for seating the cap on the container as the gases contract during continuous movement of the container.

40 8. A method according to claim 7 wherein a sweep of air is supplied beneath the cap before the combustible fluid is supplied to remove vapor therefrom.

45 9. A method according to claim 5 wherein the sealed container is subsequently subjected to me-

chanical pressure to finally seal the cap in position on the container.

10. A method according to claim 7 wherein the sealed container is subsequently subjected to mechanical pressure to finally seal the cap in position on the container.

11. Apparatus for sealing a cap on a container which comprises means for supporting and guiding a cap into position over an open container, means for sweeping moisture laden air from beneath the cap and the head space of the container while the cap is being guided into position, means for charging the air beneath the cap with a combustible fluid to form a combustible mixture and igniting said combustible mixture while the cap is being guided into position, and means for seating the cap upon the container as the combustion subsides.

12. Apparatus for sealing a cap on a container which comprises means for supporting and guiding a cap into position over an open container, means for creating a flow of air beneath the cap to remove the vapor within and about the space adjacent the open mouth of the container, means

for charging the said space with a combustible fluid to form a combustible mixture and means for igniting said combustible mixture to produce expanding burning gases, and means for seating the cap upon the container while the burning gases are expanded.

13. Apparatus for sealing caps on containers comprising a continuously moving conveyor, a cap feeding unit disposed above the conveyor for supporting the caps in position to be engaged and withdrawn by successive containers carried by the conveyor in order to apply the caps to the containers, means for creating a continuous current of air in the environment of the cap and the space adjacent the open mouth of the container to remove the vapor therefrom, means associated with the cap feeding unit for charging and igniting a combustible mixture beneath each cap as it is applied to each successive container, and control means engaged by the cap withdrawn from the cap feeding unit by the container for actuating said last-named means.

WILLIAM D. BELL.
